(57) **CLAIM**

The ornamental design for a door for refrigerator, as shown and described.

DESCRIPTION

1. Door for refrigerator

1.1 is a perspective view of a door for refrigerator, showing our new design;

1.2 is a front elevation view thereof;

1.3 is a rear elevation view thereof;

1.4 is a left-side elevation view thereof;

1.5 is a right-side elevation view thereof;

1.6 is a top plan view thereof;

1.7 is a bottom plan view thereof;

1.8 is a perspective view thereof, in a use condition;

1.9 is an exploded perspective view thereof;

1.10 is a perspective view of the door for refrigerator, with its basket moved down;

1.11 is a front elevation view thereof;

1.12 is a rear elevation view thereof;

1.13 is a left-side elevation view thereof;

1.14 is a right-side elevation view thereof;

1.15 is a top plan view thereof; and

1.16 is a bottom plan view thereof.

(Continued)

The broken lines shown in the drawing figures are included for the purpose of illustrating environment and form no part of the claimed design.

1 Claim, 16 Drawing Sheets
